BY *Victor J. Evans*

ATTORNEY

WITNESS:

UNITED STATES PATENT OFFICE.

FORTUNATO GIOMMI, OF PAWTUCKET, RHODE ISLAND.

INCUBATOR.

Application filed June 20, 1921. Serial No. 479,022.

To all whom it may concern:

Be it known that I, FORTUNATO GIOMMI, a subject of the King of Italy, residing at Pawtucket, in the county of Providence and 5 State of Rhode Island, have invented new and useful Improvements in Incubators, of which the following is a specification.

My present invention has reference to an incubator.

10 My primary object is to produce an improved heating and ventilating system for incubators.

A still further object is to produce an incubator in which the incubating chamber is 15 provided on the interior of a water circulating jacket, a packing being arranged between the exterior of the jacket and the outer body of the device, a dead air chamber being provided between the top of the 20 incubating chamber and the body, means being arranged between the incubating chamber and the exterior of the body for admitting a circulation of air into the incubating chamber, valved means being also 25 provided which serve as an outlet for foul air from the compartment, while in addition to this for humidifying the warm air in the incubating chamber.

The foregoing, and many other objects 30 which will appear as the nature of the invention is better understood, may be accomplished by a construction, combination and operative association of parts, such as is disclosed by the drawings which accompany 35 and which form part of this specification.

In the drawings:—

Figure 1 is an elevation of the improvement.

Figure 2 is a top plan view thereof.

40 Figure 3 is a sectional view on the line 3—3 of Figure 2.

Figure 4 is a sectional view on the line 4—4 of Figure 2.

Figure 5 is a horizontal sectional view approximately on the line 5—5 of Figure 1.

Figure 6 is a detail sectional view on the line 6—6 of Figure 4.

Figure 7 is a horizontal sectional view through a slight modification, in which the 50 body and water jacket are round in cross section.

The body of my improved incubator is in the nature of a substantially rectangular box-like structure and is broadly indicated 55 by the numeral 1. The body 1 is supported at its corners on legs 2.

In the body 1 there is a water circulating jacket which includes a bottom portion 3, sides 4 and ends 5. The side and end walls 4 and 5, at the top of the jacket are connected together by plates 6 which close the hollow interior of the said jacket. The substantially rectangular hollow water jacket is of a less size than that of the body 1, and the space between the said water jacket and 60 body receives therein a packing 7 of some suitable non-heat conducting material. The interior of the water jacket provides the incubating chamber and is, for distinction, indicated by the numeral 8. Resting on the 70 bottom 3 of the incubating chamber 8, adjacent to either the side or end walls thereof are upwardly extended members 9 provided at spaced intervals with transverse cleats 10. The cleats on one of the members 9 are disposed directly opposite the cleats on the opposite member, and these cleats provide supports for the reticulated egg frames 11. One or a number of such frames may be employed in accordance with the number of 80 the chicks to be hatched, and preferably each frame is provided with means whereby the eggs thereon can be turned for the well known purpose.

Resting on the closed top of the water 85 circulating drum and on the top of the packing 9 is a plate 12. This plate is provided with a central opening 13 which is closed by a transparent plate 14. The plate 12 provides what I will term the inner top 90 member for the incubating chamber, a second plate 15 being arranged on the upper edges of the body 1, and providing a dead air space 16 between the same and the plate 12. The plate 15 is also provided with a 95 central opening that is closed by a transparent plate 17. Preferably the plates 14 and 17 are received in frames that are suitably supported on flanges formed on the walls provided by the openings in the said plates 12 and 15, and consequently, the transparent plates serve as means whereby the eggs in the incubating chamber can be inspected, and also as doors whereby access can be obtained to the interior of said chamber. The cover plate 15 has arranged thereon handle members 18, and similar members may be arranged on the inner cover plate 12, or if desired this last mentioned plate may be hingedly connected to the interior 110 of the body.

The inlet for the water jacket is indicated

by the numeral 19 and is in the nature of a spout which is received through a suitable opening in the cover plate 12.

Carried by the cover plate 12, received in suitable openings therein, and passing through suitable openings in the outer cover plate 15 are a plurality of tubes 20. These tubes are preferably four in number and also preferably comprise sectional members, 10 that is an outer member which is telescoped in an inner member, the outer member having its passage controlled by a valve which is operated by a stem 21. The tubes 20 provide the outlet for foul air from the incubating chamber.

Fresh air is let into the incubating chamber through tubes 22 that are arranged adjacent to the floor of the incubating chamber. Preferably four tubes 22 are arranged 20 in spaced relation through each of the sides and ends of the water jacket, the said tubes also passing through the packing 7 and through the body 1.

The bottom of the body is, for distinction, 25 indicated by the numeral 23, the packing 7, of course, being arranged between the bottom of the body and the bottom of the water jacket. The bottom 23 is centrally provided with a notched or cut-away portion 24, the packing being likewise cut away, but being retained in proper position by angularly disposed plates 25 that provide walls for the opening 24. The plates 25 also 30 support a plate 26 that is in contact with the lower wall of the water jacket. This plate 26 is in direct contact with heat which is admitted from a heater 27 suitably supported by means 28. The heater may be in the nature of an ordinary lamp, a gas or 35 gasoline stove, or any other desired means capable of generating sufficient heat to retain the water 29 in the jacket at a temperature desirable for incubation. In this connection, it is to be stated that one of the 40 important features of the construction is the fact that the water drum is surrounded on its sides, ends and bottom by the non-heat conducting packing 7 and its top is protected by the dead air space 30 provided 45 between the cover plates 12 and 15. As a consequence, should the heater 27 be extinguished even for a reasonable period, the water in the jacket will not become sufficiently cooled to impair the temperature in 50 the incubating chamber.

The bottom of the jacket is provided with a valved outlet spout 31 that passes through the bottom of the body, the valve 32, controlling the passage of the said spout being, 55 of course, arranged exteriorly of the body.

During the process of incubation, I have found it to be desirable, if not essential that the warm air be humidified, and to accomplish this, I connect to the water jacket, ad-

jacent to the top thereof a comparatively small tube 33. The tube is arranged adjacent to one of the sides or one of the ends of the jacket, extending downwardly against said side or end and having on its lower portion a horizontal branch 34 provided with radially disposed minute apertures. The outer end of the branch 34 is closed, and the passage of the pipe 33 is controlled by a valve 35 arranged in close proximity to the doors provided by the transparent plates in 75 the cover plates 12 and 15.

It is believed that the foregoing description, when taken in connection with the drawings will fully set forth the construction and advantages of the improvement, 80 and that further detailed description will not therefore be necessary. It is to be stated, however, that the nature of the invention is such as to render the same susceptible to various changes in size, proportion, material employed, and in details of construction, and therefore I am not to be limited to the device as set forth in the specification and illustrated by the drawings, but am entitled to all such changes therefrom as 90 fall within the scope of what is claimed.

It may be found preferable to construct the body, or at least the water jacket of hollow members which are round in cross section, such construction being illustrated in 95 Figure 7 of the drawings. In the said figure, the body is indicated by the numeral 1, and the water jacket by the numeral 50. Except in shape, the details of the construction are similar to that previously described. 100 While space in the cylindrical construction is sacrificed it is believed that a more uniform heat will be produced in the incubating chamber, and the structure, as heretofore inferred is merely illustrated to indicate a modification which may be employed.

Having described the invention, I claim:

In an incubator, a leg supported body, a box-shaped water jacket in the body, a non-heat conducting packing between the water 110 jacket and the body, said body and packing having aligning openings at the bottom thereof, a plate engaging lower wall of the jacket in a line with said openings, a heater depending from said bottom and the upper 115 portion thereof being arranged between the openings for heating the water in the jacket, means at the top of the jacket for the admission of water therein, valved means at the bottom of the jacket providing an outlet for the water, the interior of the jacket providing an incubating chamber, means for removably supporting reticulated egg trays therein, a plurality of tubes arranged in spaced relation through each of the sides 120 and ends of the water jacket, said tubes being designed to pass through the packing and the body for communication with the 125

atmosphere to admit fresh air to the chamber below the trays, valved means for admitting hot water vapor from the jacket to the bottom of the chamber, a removable 5 plate covering the top of the jacket and the top of the packing, a removable transparent door carried by the plate, a second plate ar-

ranged above the first mentioned plate and resting on the upper edge of the body, and valve controlled foul air outlet pipes carried 10 by said plates.

In testimony whereof I affix my signature.

FORTUNATO GIOMMI.
